CLAIM

The ornamental design for a dosage packaging for washing agents, as shown and described.

DESCRIPTION

FIG. 1 is a top, front perspective view of a dosage packaging for washing agents showing our new design;

FIG. 2 is a top plan view thereof;

FIG. 3 is a bottom plan view thereof;

FIG. 4 is a front view thereof;

FIG. 5 is a back view thereof;

FIG. 6 is a right side view thereof; and,

FIG. 7 is a left side view thereof.

The broken lines shown represent unclaimed subject matter and form no part of the claimed design.

1 Claim, 5 Drawing Sheets
